RAILWAY TRAFFIC CONTROLLING
APPARATUS

George R. Pflasterer, Greenville, Pa., assignor to
The Union Switch and Signal Company, Swiss-
vale, Pa., a corporation of Pennsylvania

Application October 17, 1941, Serial No. 415,397

11 Claims. (Cl. 246—160)

My invention relates to railway traffic controlling apparatus, and more particularly to approach locking apparatus for use in interlocking systems for railroads, for locking a track switch against operation under certain conditions when a signal governing movement of traffic over the switch is manually put to stop. The purpose of such locking is to prevent movement of the switch when a train is approaching at such speed that it cannot be readily stopped without overrunning the switch.

In such a situation, when the stretch of track leading to the switch is occupied, it is customary to prevent movement of the switch until after the expiration of a time interval long enough to permit the train approaching the switch either to stop or to advance into the detector section and render the detector locking effective.

The systems of this type heretofore known have employed a fixed time delay period during which operation of the switch is prevented, and the systems operate so that the full time delay period is required to elapse regardless of the location of the train in the approach zone, and regardless of the speed at which the train is approaching the switch. This arrangement provides a safe system, but it may unnecessarily delay train movements.

It is an object of this invention to provide improved apparatus of the type described and incorporating means to vary the time delay interval in accordance with the location of the train in the approach zone, or with the speed of the train approaching the switch, or both, so that a short time delay period is enforced at times, and a long time delay period is enforced at other times.

Other objects of the invention and features of novelty will be apparent from the following description taken in connection with the accompanying drawings.

I shall describe two forms of apparatus embodying my invention, and shall then point out the novel features thereof in claims.

In the drawings

Fig. 1 is a diagram showing a system arranged so that a short time delay period is imposed when the portion of the approach zone in the rear of the distant signal is occupied, and a long time delay period is imposed when the portion of the approach zone in advance of this signal is occupied, and

Fig. 2 is a diagram showing a system arranged so that a short time delay period is enforced when a slow train approaches the switch and a

long time interval is enforced when a fast train is approaching the switch.

Similar reference characters refer to similar parts in each of the two views.

5 Referring to Fig. 1 of the drawings, there is shown therein a stretch of railroad track having a main track A, and a siding or branch track B which is connected with the main track A by a track switch W. The switch W is moved between the normal and reverse positions by a power operated switch machine SM which may be of any well known construction, and which is controlled by a polarized switch control relay WR in the customary manner.

10 The main track A has track rails 1 and 2 which are divided by insulated joints 3 into the usual track sections which are here designated 1T, 2T, and 3T. The track sections 1T and 2T together constitute an approach stretch or approach zone, while a detector section 3T includes the switch W and the adjacent portions of the tracks A and B.

15 Each of the track sections is provided with track circuit apparatus which may be of any well known type. As shown each section has a track battery connected across the rails of the section at one end of the section, and a track relay TR connected across the rails of the section at the other end of the section.

20 The main track A is provided with wayside signals which govern movement of trains through the track stretch in the normal direction of traffic, that is, from left to right. The wayside signals may be of any suitable type, and are here shown as being of the color light type. The home signal at the switch W has an upper portion designated SA which governs movement of trains through the main track A across the switch W, and a lower portion designated SB which governs movement of trains from the main track A across the switch W to the track B.

25 The signal SA has a green or clear lamp G, a yellow or caution lamp Y, and a red or stop lamp R, while the signal SB has a yellow or proceed lamp Y, and a red or stop lamp R.

30 A distant signal SD is located some distance from the switch W, this distance being such that trains traversing the track stretch and receiving a restrictive indication at signal SD will be able to stop before reaching the switch. The signal SD has a green or clear lamp G, a yellow or caution lamp Y, and a red or stop lamp R.

35 The distant signal SD is controlled in any appropriate manner by traffic conditions in advance of the signal so that the signal will dis-

play its read or stop indication when a train is present in section 2T. When section 2T is vacant, the signal SD is controlled in accordance with the indication displayed by signal SA so that when the signal SA is displaying its red or stop indication, the signal SD will display its yellow or caution indication, and when the signal SA is displaying its yellow or its green indication, the signal SD will display its green indication.

The means by which the signal SD is controlled in accordance with traffic conditions in advance and by the indication displayed by the signal SA is old and well known in the art and is not a part of this invention, and has not been shown in order to simplify the disclosure.

Similarly, the signal SA is controlled by traffic conditions in advance of the signal, while manually operated means is provided for also controlling the signals SA and SB. The means by which these signals are controlled is old and well known in the art and has not been shown in order to simplify the disclosure.

The supply of energy of normal or reverse polarity to the winding of the switch control relay WR is controlled by appropriate means, such as a lever L. This lever may be located at any convenient point, as for example in a signal control tower, and may form a part of an interlocking machine.

The approach locking of the switch is effected by means of an approach locking relay H which controls the circuit of the switch control relay WR to permit energization of this relay WR only when the relay H is energized, while the circuit of the relay WR is also controlled by the track relay 3TR for the detector section 3T.

The relay H has associated therewith an approach relay AR, a signal indication relay G, and auxiliary relays M, P and Q which cooperate as explained below to control circuits for supplying energy to the relay H.

The relay G is governed in any manner well known in the art so as to be energized when and only when the signals SA and SB are displaying their red or stop indications, and when, in addition, the signal SD is displaying either its yellow or its red indication.

The circuit of the relay AR is controlled by contacts of the track relays 1TR and 2TR so as to be complete only when these track relays are both picked up. The relay AR, therefore, is picked up only when the approach zone is vacant, and is released when either section of this zone is occupied.

The equipment is shown in the condition which it assumes when there are no trains in the track stretch in the vicinity of the switch W, the switch W is in its normal position, the signals SA and SB both display their red or stop indications, and the signal SD displays its yellow or caution indication.

As the approach zone is assumed to be vacant, the track relays 1TR and 2TR are picked up and energy is supplied to the relay AR over the circuit which is traced from terminal B of a source through front contact 10 of relay 1TR, wire 11, front contact 12 of relay 2TR, and winding of relay AR to terminal C of the source so that contact 14 of relay AR is picked up.

As the signals SA and SB are both assumed to be displaying stop indications, and as the signal SD is assumed to be displaying its yellow or caution indication, energy is supplied to relay G and its contact 15 is picked up.

As contact 14 of relay AR and contact 15 of relay G are picked up, the pick-up circuit of relay H is complete and is traced from terminal B of a source of current through front contact 15 of relay H, front contact 14 of relay AR, wire 16, and winding of relay H to terminal C of the source.

Accordingly, the contacts of relay H are picked up and its contact 18 establishes a stick circuit to maintain the relay winding energized after release of contact 14 of relay AR provided contact 15 of relay G remains picked up.

In addition, contacts 19 and 20 of relay H are picked up, and as contacts 22 and 23 of relay 3TR are also picked up, the circuit of the switch control relay WR is complete and this relay may be operated to move the switch W between its two positions.

As contact 25 of track relay 2TR is picked up, the circuit of relay P is interrupted, and as contact 18 of relay H is picked up, the circuit of the relay Q is interrupted. As contact 26 of relay P is released, the picked-up circuit of relay M is interrupted, and as contact 27 of relay H is picked up, the stick circuit of relay M is interrupted and this relay is deenergized and its contacts are released.

If the operator wishes to clear the signal SA, he may do so by means not shown, and when the signal control apparatus is conditioned to cause signal SA to be controlled by traffic conditions in advance, the signal SA will display its green or clear indication as the track stretch is assumed to be vacant. On this change in the aspect of signal SA signal SD is conditioned to display its green instead of its yellow indication; while on this change in the aspects of signals SA and SD relay G becomes released and its contact 15 interrupts the pick-up and stick circuits for relay H so that the contacts of relay H release and its contacts 19 and 20 interrupt the circuit of relay WR to thereby prevent movement of the switch W.

If a train moving from left to right now enters section 1T, track relay 1TR will release and its contact 10 will interrupt the circuit of the relay AR so that contact 14 of relay AR interrupts the pick-up circuit of the relay H to prevent energization of the relay H in the event of picking up of contact 15 of relay G.

If, while the train is in section 1T, and before it enters section 2T the operator decides to change the position of the switch W, he may do so after expiration of a short time interval providing he secures control of the switch before the train passes signal SD and enters section 2T.

In order to secure control of the switch the operator must first cause signal SA to again display its stop indication, while when this signal shows stop, the signal SD will display its yellow or caution indication. When signal SA shows stop and signal SD shows caution, energy is supplied to relay G and its contact 15 picks up and establishes a circuit including back contact 18 of relay H, wire 30, and back contact 31 of relay P for supplying energy to the slow pick-up relay Q. After a predetermined time interval the contacts of the relay Q pick up.

If at the time the contacts of relay Q pick up the train in section 1T has not advanced into section 2T and track relay 2TR is picked up, a pick-up circuit will be established for relay H. This circuit is traced from terminal B through front contact 15 of relay G, front contact 33 of track relay 2TR, wire 34, front contact 35 of relay

Q, and wire 16 to one terminal of the winding of relay H.

Accordingly, energy will be supplied to relay H and its contacts will pick up so that its contact 18 establishes a circuit to maintain the relay energized as long as the contact 15 of relay G remains picked up.

On picking up of the contacts of relay H its contact 18 interrupts the circuit for supplying energy to the relay Q so that relay Q releases, and its contact 26 interrupts the circuit traced above for supplying energy to the relay H. However, the relay H is maintained energized by current supplied over its own front contact 18, and contacts 19 and 20 of relay H are picked up and the circuit of the switch control relay WR is complete so that the switch W may be moved.

Movement of the switch at this time is proper as the train approaching the switch will have received a restrictive indication when it passes signal SD and will be approaching signal SA prepared to stop.

After completing movement of the switch the operator may condition the appropriate one of the signals SA or SB to display a process indication, and when this is done relay G releases and its contact 15 interrupts the supply of energy to the relay H so that the contacts 19 and 20 of relay H release and interrupt the circuit of the switch control relay WR to thereby prevent further movement of the switch.

If the train advances into section 2T before the operator decides to move the switch, or before he obtains control of the switch, a longer time interval must elapse before the operator can secure control of the switch.

When a train is present in either section 1T or 2T, relay AR is released, while when the train advances into section 2T, track relay 2TR releases. As the signal SA or SB is assumed to be displaying a proceed indication, relay G is de-energized and its contact 15 interrupts the circuit of the relay H so that the contacts of relay H are released.

If the operator now causes the signals SA and SB to both display stop indications, relay G will be energized and its contact 15 will be picked up. At this time contact 14 of relay AR is released and interrupts the pick-up circuit of relay H so that relay H remains released.

On picking up of relay G energy is supplied to relay Q over the circuit which is traced from terminal B through front contact 15 of relay G, wire 16, back contact 18 of relay H, wire 30, back contact 31 of relay P, and winding of relay Q to terminal C. After a time interval determined by the pick-up time of the relay Q the contacts of this relay become picked up, and as section 2T is occupied and track relay 2TR is released, its contact 33 interrupts the circuit traced above for supplying energy to the relay H so that the operator does not secure control of the switch at this time. On picking up of the contacts of relay Q a circuit is established to energize the relay P. This circuit is traced from terminal B through back contact 25 of relay 2TR, winding of relay P, and front contact 37 of relay Q to terminal C.

On picking up of the contacts of the relay P its contact 31 interrupts the circuit of the relay Q with the result that the contacts of relay Q release and its contact 37 interrupts the circuit of relay P. The relay P, however, is of a type the contacts of which are slow in releasing so that its contacts remain picked up for a period subsequent to release of the contacts of relay Q.

On release of relay Q the pick-up circuit of relay M is complete and is traced from terminal B through back contact 38 of relay Q, front contact 26 of relay P, and winding of relay M to terminal C. Accordingly, the contacts of relay M pick up and its contact 39 establishes a stick circuit for the relay. This circuit is traced from terminal B through front contact 15 of relay G, back contact 14 of relay AR, back contact 27 of relay H, front contact 39 of relay M, and winding of relay M to terminal C. The contacts of relay M, therefore, will remain picked up after release of the contacts of relay P.

On release of the contacts of relay P the circuit traced above for energizing the relay Q is reestablished, and after a time interval the contacts of this relay pick up with the result that a pick-up circuit for the relay H is established. This circuit is traced from terminal B through front contact 15 of relay G, front contact 40 of relay M, wire 34, front contact 35 of relay Q, wire 16, and winding of relay H to terminal C. Accordingly, the contacts of relay H pick up and contact 27 interrupts the stick circuit for relay M, while contact 18 of relay H interrupts the circuit of relay Q and establishes a stick circuit to energize the relay H as long as relay G remains energized.

On picking up of the contacts of the relay H the circuit of the switch control relay WR is complete providing the train has not advanced beyond the signals SA and SB and entered section 3T so that the track relay 3TR is released and renders the detector locking effective. Accordingly, on picking up of the relay H the operator obtains control of the switch and may move it to either position.

It will be seen that after a train enters section 2T, the operator can secure control of the switch only after the expiration of a time interval determined by two operations of the relay Q. This time interval is long enough to permit the train in section 2T either to stop or to advance into section 3T and thereby render the detector locking effective.

From the foregoing it will be seen that the system shown in Fig. 1 operates to permit the operator to gain control of the switch after the expiration of a short time interval when a train is in the section in the rear of the distant signal, while the system operates so that when a train is present in the section between the home and distant signals, the operator can obtain control of the switch only after the expiration of a longer time interval.

It will be seen that the system provided by this invention operates to permit the switch to be moved only when it is safe to do so, while the system also operates so that movement of the switch is not delayed any longer than is necessary.

When a train is in the section in the rear of the distant signal, a short time interval is imposed before the switch can be moved. This is sufficient as the train will receive a restrictive indication from the distant signal and will be prepared to stop before it reaches the switch.

If the train is in the section in advance of the distant signal when the home signal is placed at stop, a long time interval must elapse before the switch can be moved. This insures that the train can either stop before reaching the switch or that it will overrun the home signal and render the detector locking effective before the approach locking is released.

Furthermore, the system is arranged so that if the train which was in the section in the rear of the distant signal at the time the home signal was placed at stop should advance beyond the distant signal before the expiration of the short time interval, the operator cannot obtain control of the switch until the expiration of the long time interval. This method of operation insures that the switch can be moved after the expiration of the short time interval only if the train is in the rear of the distant signal for a substantial period after this signal has been caused to display its caution indication so that the engineer of the train has ample opportunity to view the signal.

The system provided by this invention may also be employed to vary the time delay interval in accordance with the speed at which a train is approaching the switch so that a short time interval is imposed when a slow train is approaching the switch while a long time interval is imposed when a fast train is approaching the switch, and Fig. 2 is a diagram showing this modification of the invention.

The modification shown in Fig. 2 is similar to that shown in Fig. 1, but differs therefrom in that the track stretch intermediate the signals SA and SD is divided into two sections designated A2T and B2T, while an additional auxiliary relay V is employed to assist in the control of the relay H.

The equipment of Fig. 2 is shown in the condition which it assumes when there are no trains in the track stretch in the vicinity of the switch W, the switch W is in its normal position, the signals SA and SB both display their red or stop indications, and the signal SD displays its yellow or caution indication.

As the approach zone is assumed to be vacant, the track relays 1TR, A2TR and B2TR are picked up, and energy is supplied to the relay AR so that its contacts are picked up. As the home signals SA and SB are both assumed to be displaying stop indications, and as the distant signal SD is assumed to be displaying its caution indication, energy is supplied to the relay G and its contact 15 is picked up. As contact 15 of relay G and contact 14 of relay AR are picked up, the pick-up circuit of relay H is complete, and the contacts of this relay are picked up so that contact 18 establishes a stick circuit to maintain the contacts of relay H picked up as long as contact 15 of relay G is picked up.

As contacts 19 and 20 of relay H are picked up, and as the contacts 22 and 23 of relay 3TR are also picked up, the circuit of the switch control relay WR is complete and the operator may change the polarity of the energy supplied to this relay and thereby cause the switch to be moved.

At this time contact 18 of relay H interrupts the circuit of the relay Q, contact 37 of relay Q interrupts the circuit of the relay P, contact 26 of relay P interrupts the circuit of relay M, and contact 49 of relay A2TR interrupts the pick-up circuit of relay V. Accordingly, the relays M, P, Q and V are released.

If the operator wishes to clear the signal SA, he may do so by means not shown, and this signal will thereupon display its green or clear indication as the track stretch in advance is vacant. On this change in the aspect of signal SA signal SD will display its green or clear indication, while on this change in the aspects of the signals relay G releases and its contact 15

interrupts the pick-up and stick circuits for relay H so that the contacts of relay H release and interrupt the circuit of the switch control relay WR to prevent movement of the switch W.

5 If a train moving from left to right enters section 1T, the track relay 1TR will release and its contact 19 will interrupt the circuit of the approach relay AR so that contact 14 of relay AR interrupts the pick-up circuit of the relay H to prevent energization of the relay H in the event of picking up of the contact 15 of relay G.

If, after the train enters the section 1T, the operator places the signal SA at stop, the signal SD will display its caution indication and energy

15 will be supplied to the relay G so that contact 15 of this relay picks up and establishes a circuit to energize relay Q. This circuit is traced from terminal B through front contact 15 of relay G; back contact 18 of relay H; back contact 34 of relay P; and winding of relay Q to terminal C. After a time interval the contacts of the relay Q pick up, and if they pick up before the train advances into section A2T, a pick-up circuit for the relay H will be established; and

25 the contacts of relay H will pick up and establish a stick circuit for the relay and also establish the circuit of the switch control relay WR to permit the switch to be moved.

The pick-up circuit for the relay H which is established on picking up of the contacts of the relay Q is traced from terminal B through front contact 15 of relay G; front contact 43 of relay A2TR; front contact 44 of relay B2TR; front contact 45 of relay Q; wire 16; and winding of relay H to terminal C.

If, therefore, the train remains in section 1T until after the contacts of relay Q become picked up, the operator will secure control of the switch after one operation of the contacts of the relay Q. This is proper as the train in section 1T will have been in that section for a substantial time interval and the engineer of the train will have had ample opportunity to see the distant signal SD.

45 If the train advances into section A2T before the contacts of relay Q become picked up, contact 43 of track relay A2TR will be released so that on picking up of the contacts of relay Q the above traced pick-up circuit for the relay H will not be established. Instead a pick-up circuit for the relay V will be established. This circuit is traced from terminal B through front contact 15 of relay G; back contact 14 of relay AR; back contact 21 of relay H; front contact

55 48 of relay B2TR; back contact 40 of relay A2TR; and winding of relay V to terminal C.

The pick-up time of the relay V and the length of the section A2T are selected and proportioned so that the time required for a train to traverse section A2T is greater than the pick-up time of relay V if the train speed is below a predetermined rate, and is less than the pick-up time of the relay V if the train speed is greater than the predetermined rate. This predetermined rate and the length of the section B2T are such that a train traveling at this or a slower rate will be able to stop without difficulty before reaching the switch.

After a predetermined time interval the contacts of relay V pick up, assuming that the train speed is less than the predetermined rate, and contact 42 of relay V establishes a stick circuit shunting the contacts of track relays A2TR and B2TR, while contact 46 of relay V cooperates with contact 41 of relay Q to establish a pick-up

70 circuit for the relay H. Assuming that the train speed is greater than the predetermined rate, contact 42 of relay V will not pick up, and contact 46 of relay V will not establish a stick circuit shunting the contacts of track relays A2TR and B2TR, while contact 46 of relay V cooperates with contact 41 of relay Q to establish a pick-up

circuit for relay H. This pick-up circuit for relay H is traced from terminal B through front contact 15 of relay G, front contact 46 of relay V, front contact 41 of relay Q, wire 16, and winding of relay H to terminal C.

If, therefore, the train is traveling at a speed below the predetermined value so that the contacts of relay V become picked up before the train advances into section B2T, a pick-up circuit for relay H will be established on picking up of the relay V and the operator will have control of the switch. This is proper as the train must have been moving slowly not to have passed through section A2T before the contacts of relay V become picked up and the train will be able to stop before it reaches the switch.

When the contacts of relay H pick up, contact 18 establishes a stick circuit to maintain the relay energized, while contact 18 interrupts the circuit for supplying energy to the relay Q so that the contacts of this relay release. In addition, on picking up of the contacts of relay H contact 27 interrupts the circuit for supplying energy to the relay V and the contacts of this relay release.

If the train is traveling in excess of the predetermined rate, it will advance into section B2T before the contacts of relay V become picked up and contact 41 of relay B2TR will interrupt the pick-up circuit of relay V and thus prevent picking up of the contacts of this relay. In addition, on release of the relay B2TR its contact 25 establishes the circuit of the relay P. This circuit is traced from terminal B through back contact 25 of relay B2TR, winding of relay P, and front contact 37 of relay Q to terminal C.

Accordingly, the contacts of relay P pick up and its contact 31 interrupts the circuit of the relay Q, while contact 26 of relay P establishes a circuit to supply energy to relay M after release of the contacts of relay Q. As a result of interruption of the circuit of relay Q by contact 31 of relay P, the contacts of relay Q release and contact 37 of relay Q interrupts the circuit traced above for energizing the relay P so that the contacts of relay P release. However, because of the slow releasing characteristic of the relay P the contacts of this relay remain picked up for a short time interval subsequent to release of the contacts of relay Q so that a pick-up circuit including back contact 38 of relay Q and front contact 26 of relay P is established to supply energy to the relay M. The contacts of relay M, therefore, pick up and its contact 39 establishes a stick circuit to maintain the relay contacts picked up. This stick circuit is traced from terminal B through front contact 15 of relay G, back contact 14 of relay AR, back contact 27 of relay H, front contact 39 of relay M, and winding of relay M to terminal C.

On release of the contacts of relay P following release of the contacts of relay Q contact 26 of relay P interrupts the pick-up circuit of relay M, but this relay is maintained energized by current supplied over its stick circuit. On release of contact 31 of relay P the circuit of relay Q is reestablished and this relay starts a new or second cycle of operation.

After a time interval the contacts of relay Q become picked up and a pick-up circuit for the relay H is established which is traced from terminal B through front contact 15 of relay G, front contact 40 of relay M, front contact 47 of relay Q, wire 16, and winding of relay H to terminal C. Accordingly, the contacts of relay H pick up

and its contact 18 establishes a circuit to maintain the relay winding energized, while its contact 18 interrupts the circuit of relay Q and its contact 27 interrupts the circuit of relay M so that the contacts of these relays release. As the contacts of the relay H are picked up, the circuit of the switch control relay WR is complete and the operator may move the switch as desired.

From the foregoing it will be seen that the system shown in Fig. 2, like that shown in Fig. 1 operates so that if the operator attempts to secure control of the switch while a train is in section IT, and the relay Q completes one cycle of operation before the train enters section A2T, the operator will obtain control of the switch after the expiration of the time interval required for the contacts of the relay Q to pick up.

However, if the train advances into section A2T before the contacts of relay Q become picked up, the operator will not secure control of the switch upon picking up of the contacts of relay Q. Instead on entrance of the train into section A2T a circuit for the relay V is established. If the speed of the train is such that the contacts of relay V become picked up before the train traverses section A2T and enters section B2T, the contacts of relay V will pick up and establish a pick-up circuit for relay H to thereby give the operator control of the switch. However, if the train speed is such that the train advances into section B2T before the contacts of relay V pick up, the circuit for energizing relay V is interrupted, while the system operates like that shown in Fig. 1 so that the operator secures control of the switch only after two cycles of operation of the relay Q.

This method of operation provides a safe system as it permits the operator to gain control of the switch after a short time interval providing this interval is completed before the train passes the distant signal and enters section A2T. If this short time interval does expire before the train enters section A2T, the system operates to give the operator control of the switch after expiration of a further short time interval if the train is traveling at a slow speed. This is desirable as it enables the operator to quickly secure control of the switch at times when a train in the approach zone is moving slowly and the attempt to secure control of the switch is not made until the train is relatively near the distant signal so that it advances beyond this signal and enters section A2T before sufficient time has elapsed for the contacts of relay Q to become picked up. It is safe for the operator to secure control of the switch at such times as the train is moving slowly and will be able to stop before reaching the home signal, while ability of the operator to quickly gain control of the switch at such times enables him to route trains without delay and thus facilitates movement of traffic across the switch.

The system provided by this invention is safe as the system operates when a fast train passes through the approach zone to prevent acquisition of control of the switch by the operator until the expiration of the time interval determined by two cycles of operation of the relay Q. This time interval is long enough to enable the train either to stop or to overrun the home signal and enter the detector section and thus render the detector locking effective.

Although I have herein shown and described only two forms of apparatus embodying my invention, it is understood that various changes

and modifications may be made therein within the scope of the appended claims without departing from the spirit and scope of my invention.

Having thus described my invention, what I claim is:

1. In combination, a stretch of railway track containing a switch movable between a normal and a reverse position and including an approach zone of track leading to said switch, said approach zone being divided into a plurality of track sections including a first section remote from the switch and a second section adjacent the switch, an approach locking relay controlling the switch and effective when deenergized to prevent movement of the switch, means effective when said first section is occupied and said locking relay is deenergized to establish a circuit to supply energy to the locking relay after the expiration of a predetermined time interval, means responsive to occupancy of said second section for interrupting said circuit for supplying energy to said locking relay, a signal governing movement of traffic across said switch, and means for deenergizing said locking relay when said signal indicates proceed and to permit energy to be supplied to said locking relay only when said signal indicates stop.

2. In combination, a stretch of railway track containing a switch movable between a normal and a reverse position and including an approach zone of track leading to said switch, said approach zone being divided into a plurality of track sections, including a first section remote from the switch and a second section adjacent the switch, an approach locking relay controlling the switch and effective when deenergized to prevent movement of the switch, a timing relay having a normally open contact which on the supply of energy to the relay becomes closed on the expiration of a predetermined time interval, a pick-up circuit for said locking relay including in series therewith a contact of said timing relay, means effective when said first section is occupied and the locking relay is deenergized to establish a circuit to supply energy to said timing relay, means responsive to occupancy of said second section for interrupting the pick-up circuit for said locking relay, a signal governing movement of traffic across said switch, and means for deenergizing said locking relay when said signal indicates proceed and to permit energy to be supplied to said locking relay only when said signal indicates stop.

3. In combination, a stretch of railway track containing a switch movable between a normal and a reverse position, an approach zone of track leading to said switch, said approach zone being divided into a plurality of track sections including a first section remote from the switch and a second section adjacent the switch, each of said sections being provided with a track relay which is released when the section is occupied, an approach locking relay controlling the switch and effective when deenergized to prevent movement of the switch, a slow pick-up relay having a normally open contact which on the supply of energy to the relay becomes closed on the expiration of a predetermined time interval, a slow releasing relay, an auxiliary relay, a circuit including back contacts of the locking relay and said slow releasing relay for supplying energy to said slow pick-up relay, a circuit including a front contact of said slow pick-up relay and a back contact of said second section track relay for supplying energy to said slow releasing relay, a

circuit including a front contact of the slow releasing relay and a back contact of the slow pick-up relay for supplying energy to the auxiliary relay, a pick-up circuit for the locking relay including front contacts of the second section track relay and of said slow pick-up relay, a third pick-up circuit for said locking relay including front contacts of said auxiliary relay and of said slow pick-up relay, a fourth pick-up circuit over which

10 energy may be supplied to said locking relay when the track relays for said first and second sections are picked up, a signal governing movement of traffic across said switch, and means for deenergizing said locking relay when said signal indicates proceed and to permit the pick-up circuits for said locking relay to be established only when said signal indicates stop.

4. In combination, a stretch of railway track containing a switch movable between a normal and a reverse position and including an approach zone of track leading to said switch, said approach zone being divided into a first section remote from the switch, a second section adjacent the switch and an intermediate section located between said first and second sections, a lock relay controlling the switch and effective when deenergized to prevent movement of the switch, means effective when said first section is occupied for establishing a first pick-up circuit to supply energy to said lock relay after the expiration of a predetermined time interval, means effective on occupancy of said intermediate section to prevent establishment of said first pick-up circuit, means responsive to occupancy of the intermediate section for establishing a second pick-up circuit to supply energy to said lock relay after the expiration of a predetermined time interval, means effective on occupancy of said second section for establishing a third pick-up circuit to supply energy to said lock relay after the expiration of a predetermined time interval, a signal governing movement of traffic across said switch, and means for deenergizing said lock relay when said signal indicates proceed and to permit the pick-up circuits for said lock relay to be established only when said signal indicates stop.

5. In combination, a stretch of railway track containing a switch movable between a normal and a reverse position and including an approach zone of track leading to said switch, said approach zone being divided into a first section remote from the switch, a second section adjacent the switch and an intermediate section located between said first and second sections, each of said sections having a track circuit including a track relay which is released when the section is occupied, a lock relay controlling the switch and effective when deenergized to prevent movement of the switch, a first and a second slow pick-up relay, a slow releasing relay and an auxiliary relay, a circuit including back contacts of the lock relay and of the slow releasing relay for supplying energy to the first slow pick-up relay, a first pick-up circuit for the lock relay including front contacts of the first slow pick-up relay and of the track relays for the intermediate and second sections, a pick-up circuit for the second slow pick-up relay including a back contact of the intermediate section track relay and a front contact of the second section track relay, a second pick-up circuit for the lock relay including front contacts of the first and second slow pick-

up relays, a circuit including a back contact of the second section track relay and a front contact of the first slow pick-up relay for energizing the slow releasing relay, a pick-up circuit for the auxiliary relay including a front contact of the slow releasing relay and a back contact of the first slow pick-up relay, a stick circuit for the auxiliary relay including its own front contact and a back contact of the lock relay, a third pick-up circuit for the lock relay including front contacts of the auxiliary relay and of the first slow pick-up relay, a fourth pick-up circuit over which energy may be supplied to the lock relay when the track relays for the first, intermediate and second track sections are picked up, a signal governing movement of traffic across said switch, and means for deenergizing said lock relay when said signal indicates proceed and to permit the pick-up circuits for said lock relay to be established only when said signal indicates stop.

6. In combination, a stretch of railway track containing a track switch movable between a normal and a reverse position and including an approach zone of track leading to said switch, said approach zone being divided into a first section remote from the switch and a second section adjacent the switch, an approach locking relay effective when deenergized to prevent movement of the switch and effective when energized to permit the switch to be moved, means effective when said first section is occupied and said locking relay is deenergized to establish a first pick-up circuit to supply energy to said locking relay after a predetermined time interval, means responsive to occupancy of the second section when said locking relay is deenergized to prevent establishment of said first pick-up circuit and to establish a second pick-up circuit to supply energy to said locking relay after a predetermined time interval, said locking relay being effective when energized to establish a stick circuit to maintain itself energized, a signal governing movement of traffic across said switch, and means for deenergizing said locking relay when said signal indicates proceed and for permitting the pick-up and stick circuits for said locking relay to be established only when said signal indicates stop.

7. In combination, a stretch of railway track containing a track switch movable between a normal and a reverse position and including an approach zone of track leading to said switch, said approach zone being divided into a first section remote from the switch and a second section adjacent the switch, an approach locking relay effective when deenergized to prevent movement of the switch, an auxiliary relay having a normally open contact which on the supply of energy to the relay winding becomes closed after a predetermined time interval, means effective when said first or said second section is occupied and the locking relay is deenergized to supply energy to said auxiliary relay, means effective on closing of the contact of said auxiliary relay when said second section is vacant to establish a pick-up circuit to supply energy to said locking relay, means effective on initial closing of the contact of said auxiliary relay when the second section is occupied to interrupt the supply of energy to said auxiliary relay and effective on the second closing of said auxiliary relay contact to establish a pick-up circuit to supply energy to said locking relay, said locking relay being effective when energized to establish a stick circuit to maintain itself energized, a signal governing

movement of traffic across said switch, and means for deenergizing said locking relay when said signal indicates proceed and for permitting the pick-up and stick circuits for said locking relay to be established only when said signal indicates stop.

5 8. In combination, a stretch of railway track containing a track switch movable between a normal and a reverse position and including an approach zone of track leading to said switch, said approach zone being divided into a first section remote from the switch and a second section adjacent the switch, an approach locking relay effective when deenergized to prevent movement of the switch, means effective when said first section is occupied, the locking relay is deenergized and the second section is vacant to supply energy to said locking relay after a predetermined time interval, means effective on entrance of a train into the second section prior to the 10 expiration of said predetermined time interval to prevent the supply of energy to said locking relay by said first named means and to supply energy to said locking relay after a further predetermined time interval, said locking relay being effective when energized to establish a stick circuit to maintain itself energized, a signal governing movement of traffic across said switch, and means for deenergizing said locking relay when said signal indicates proceed and to permit the pick-up circuits for said lock relay to be established only when said signal indicates stop.

15 9. In combination, a stretch of railway track containing a track switch movable between a normal and a reverse position and including an approach zone of track divided into a plurality of sections including a first section at the end of the approach zone remote from the switch, an approach locking relay effective when deenergized to prevent movement of the switch, means effective when said first section is occupied, the locking relay is deenergized and the remainder of the approach zone is vacant to supply energy to said locking relay after a predetermined time interval, means effective on entrance of a train into the portion of the approach zone intermediate said first section and the switch when the locking relay is deenergized to prevent the supply of energy to said locking relay by the first named means and to supply energy to said locking relay after a further time interval of one length if the train is traveling at less than a predetermined rate and to supply energy to said locking relay after a further time interval of greater length if the train is traveling in excess of said predetermined rate, said locking relay being effective when energized to establish a stick circuit to maintain itself energized, a signal governing movement of traffic across said switch, and means for deenergizing said locking relay when said signal indicates proceed and for permitting energy to be supplied to said locking relay only when said signal indicates stop.

20 10. In combination, a stretch of railway track containing a track switch and including an approach zone of track divided into a plurality of sections including a first section at the end of the approach zone remote from the switch, an approach locking relay effective when deenergized to prevent movement of the switch, means effective when said first section is occupied and the remainder of said approach zone is vacant to establish a pick-up circuit to supply energy to said locking relay after a predetermined time interval, means effective on entrance of a train 25 into the portion of the approach zone intermediate

immediate said first section and the switch to prevent establishment of said pick-up circuit, a signal governing movement of traffic across said switch, and means for deenergizing said locking relay when said signal indicates proceed and for permitting energy to be supplied to said locking relay only when said signal indicates stop.

11. In combination, a stretch of railway track containing a track switch and including an approach zone of track divided into a plurality of sections including a first section at the end of the approach zone remote from the switch, an approach locking relay effective when deenergized to prevent movement of the switch, means effective when said first section is occupied and the remainder of said approach zone is vacant

to establish a pick-up circuit to supply energy to said locking relay after a predetermined time interval, means effective on entrance of a train into the portion of the approach zone intermediate said first section and the switch to prevent establishment of said pick-up circuit and to establish another pick-up circuit to supply energy to said locking relay after a further predetermined time interval, a signal governing movement of traffic across said switch, and means for deenergizing said locking relay when said signal indicates proceed and for permitting energy to be supplied to said locking relay only when said signal indicates stop.

GEORGE R. PFLASTERER.
